UNITED STATES PATENT OFFICE.

RICHARD HATLEY BERKLEY, OF PLAINVILLE, MASSACHUSETTS, ASSIGNOR TO WHITING & DAVIS COMPANY, A CORPORATION OF MASSACHUSETTS.

MACHINE FOR MAKING LINK MESH.

Application filed March 9, 1926. Serial No. 93,375.

This invention relates to machines for making link mesh fabric of the type commonly designated fish-scale mesh, which consists of a multiplicity of rings, connected by plate members of cruciform shape. Such mesh is widely used in the manufacture of articles of jewelry, such as ladies' hand bags, and as ordinarily made, the plates have plane surfaces of considerable extent which lie somewhat above the plane of the rings. When these flat surfaces are polished, the mesh has an attractive appearance which makes its use highly desirable in some types of articles due to the reflection of light from these surfaces.

I have found that the appearance of the mesh may be considerably altered by appropriately treating the flat surfaces of the plate members, in such manner that the plates no longer have plane reflecting surfaces, but these surfaces are broken or irregular, due to small projections thereon. Such mesh has a less glittering appearance than one in which the plates are smooth, and for some purposes the new mesh is preferable to the old.

The present invention is directed to the provision of a machine for making this new type of mesh fabric, and it includes mechanism for acting on the plate members to alter their appearance, prior to their introduction into the mesh.

In this new machine, supplies of rings and plate members in the form of strips of metal are provided and feeding devices are used which advance the strips with a step by step motion to devices which sever separate rings and plates from the strips, interlink the plates with the rings and with other rings at the edge of the piece of fabric previously made, and close the legs of the plates to lock the plates and rings together. In this feeding movement, the strip of plates passes suitable mechanism, brought into action at each period of rest in the step by step movement, and operating on the flat surfaces of the plates to alter their appearance. This mechanism operates in appropriate time relation to the other devices of the machine, and acts on the plates in the strip successively to produce the desired result. The machine accordingly utilizes plate material of the usual kind, but changes the appearance of the individual plates prior to their introduction into the mesh.

For a better understanding of the invention, reference will now be made to the accompanying drawings in which—Fig. 1 is a horizontal plan view of the machine; Fig. 2 is a plan view of a piece of mesh made according to the invention; Fig. 3 is a view of certain parts of the operating mechanism including the treating mechanism; Figs. 4 and 5 are views of the strips of links; Fig. 6 is an enlarged detail view of the dies.

Referring to the drawings the table of the machine is shown at 1. A support for holding a piece of mesh is mounted in a vertical position upon the table 1, and consists of a stationary mandrel 2 and a rotatable sleeve 3 enclosing a part of the mandrel. A piece of mesh is held between the mandrel and the sleeve, and the sleeve is rotated step by step to advance the piece of mesh, and at each step in the movement a mesh forming mechanism operates to add additional links at the edge of the piece of mesh. The sleeve 3 is advanced by means of a pawl 5 which engages ratchet teeth 4 on the sleeve, the pawl being mounted on a vertical pin 6 rigidly connected to an arm 7 which is engaged by a spring 8. The pawl is operated to move the sleeve step by step by a horizontal rod 9, one end of which engages a cam 10 mounted upon a power shaft 11. The cam, acting through the rod and pawl advances the sleeve one step, and the spring 8 returns the pawl to normal position in which position the member 7 is stopped by contacting with the frame of the machine as shown at 12. A retaining pawl 13 secured to a stationary part of the frame engages the ratchet teeth and prevents backward movement of the sleeve.

The ring links and the plate links are fed to the machine in the form of continuous strips as shown in Figs. 4 and 5. The strip of rings is wound upon a spool 20 at one side of the mandrel and the strip is led through a guide 21 to the mesh forming mechanism. The strip of links is wound upon a spool 22 at the opposite side of the mandrel and is directed to the mesh forming mechanism through a guide 23. A spring pressed feeding finger 25 engages the strip of rings in the guide 21, and this finger is operable by the rod 26 and cam 27 mounted upon the shaft 11, to advance the strip step by step, and thus present a ring to the mesh forming mechanism in each

- step. The finger 25 is carried by a pivoted bell crank 28. A spring 29 holds one arm of the bell crank in contact with the rod 26, and the rod in contact with the cam 27.
- 5 The strip of plates is fed to the mesh forming mechanism by a feeding finger 25' similar to that which feeds the strip of rings and carried by a bell crank 28', moved by a rod 30 and cam 31 on drive shaft 11.
- 10 At each operation of the feeding devices for the strips of rings and plates appropriate mechanism operates to sever a ring and a plate from the strips, to link ring and plate together and to interlock the plate with the
- 15 piece of mesh held by the support. This mechanism includes a reciprocable hollow plunger 35, one end of which is held in contact with a cam 36, mounted upon the power shaft 11, by a spring 37. An anvil 38, which
- 20 is carried by a rod 39, co-operates with the plunger 35, the rod 39 extending toward the power shaft and being held in contact with a cam 40 thereon by a spring 41. The rod 39 passes through a block 42, and has a pin 43
- 25 which projects through a slot 45 in the block. This slot has a portion which extends parallel to the rod 39, and another portion which extends at an angle to the rod. As the rod is reciprocated by its cam, the pin slides in
- 30 the slot, and when the pin enters the angular portion of the slot the shaft is rocked, and the anvil moved out of alignment with the plunger 35.
- 35 The plunger 35 is moved by the cam 36 and engages the end plate 50 of the strip which projects beyond the end of the guide 23, and the edge of the hollow plunger co-operates with the edge of the guide 23 to
- 40 sever the plate 50 from the strip. In this same movement, the hollow plunger forces the severed plate over the anvil 38, and the plate is bent into the form of a staple. The cam 40 now moves the shaft 39 and anvil 38 causing the anvil to recede from the plunger
- 45 a short distance, when the shaft is rocked by reason of the pin 43 sliding in the angular portion of the slot 45, and the anvil is positioned out of alignment with the plunger. The staple shaped plate remains in the hollow plunger.
- 50 The hollow plunger is now further moved by its cam toward the piece of mesh on the support. At the end of this movement, one of the four projecting ends of the staple shaped plate enters a ring 51, which projects from the guide 21, and the three other projecting ends are linked with three rings of the piece of mesh already formed and held by the support. In this further movement
- 55 of the plunger, one edge of it co-operates with the end of the guide 21, and severs the ring 51 from the strip of rings in the guide with a shearing action.
- 60 Within the hollow plunger 35 is a die rod 60, the end 61 of which is held in engagement with a cam 62 on shaft 11 by a spring 63. The cam 62 moves this die rod concurrently with the hollow plunger, when the latter moves to sever the link 50, to shape the link by co-action with the anvil, and to position
- 65 the staple shaped link with its four projecting ends linked with the ring 51 and with rings of the piece of mesh on the support. Positioned within the mandrel, is a die member 65 (Fig. 3) which is carried by a
- 70 rod 66, the end of which is connected to a bell crank 67 pivoted on the frame. One end of this bell crank is in engagement with a cam 68 mounted upon the power shaft 11. When the staple shaped plate is positioned
- 75 with one of its projecting ends extending through the ring link 51, and the other three projecting ends extending through three rings of the piece of mesh, the cam 62 operates to move the die rod 60 relatively to
- 80 the plunger 35, and the cam 68 operates, through the bell crank, to retract the die member 65. This movement of the die rod 60 expels the staple shaped link from the
- 85 end of the hollow plunger 35, and as the die rod and the die-member approach each other, the ends of the plate are turned inwardly thereby sufficiently to cause an interlock between the plate and the rings.
- 90 As the strip of plates is fed to the link forming mechanism, each plate is subjected to treatment for breaking up the continuity of the body portion of the plate. For this purpose a block 70 is mounted on the base of the machine at one side of the guide 23, and a block 71 is mounted on the opposite side of the guide. Within the blocks are co-acting die members 72 and 73. The die member 72 lies within a recess in block 70 and is adjustable in position by means of an adjustment
- 95 screw 74. The die 73 lies in a recess in block 71, and has a reduced end 75 which extends out of the end of the recess and a coil spring 76 acts upon the die 73 to hold it in retracted position.
- 100 In the operation of the machine, the plates in the strip are brought successively into alignment with the dies by the feeding device and at the proper instant, a blow is delivered to the die 73, causing it to act on the
- 105 plate in front of it. For this purpose a hammer 80 is provided, slidably mounted in a sleeve 81 which is mounted on a bracket 82 on the base of the machine. A collar 86 is secured to the hammer, and this collar is
- 110 engaged by the projecting end 87 of a rod 88. The opposite end of the rod 88 is acted on by a cam 89 mounted upon the power shaft 11. The end of the hammer which lies within the sleeve, is of reduced diameter and is encircled by a coil spring 83. This spring tends to force the hammer toward the die 73 and also holds the rod 88 in contact with the cam 89. When the cam 89, acting through the
- 115 rod 88, permits the hammer to be moved to
- 120
- 125
- 130

ward the die 73, such movement of the hammer is caused by the spring 83.

The exterior surface of the sleeve 81 is screw threaded, and the sleeve is adjustably held in the bracket 82 by the nuts 84 and 85. By adjusting the position of the sleeve in the bracket, the compression of the spring 83 may be regulated, thus permitting a control of the force of the blow delivered by the hammer. The reduced end of the hammer may extend beyond the end of the sleeve, and lock nuts 90 may be placed thereon. These nuts contact with the end of the sleeve in the die striking movement of the hammer so as to limit this movement. By these adjustments the force with which the dies strike the plates can be determined with that precision required in the making of mesh which is to be used in articles of jewelry.

The machine operates in step by step movements and at each step, a ring and a plate are advanced to the link forming mechanism and interlocked with the piece of mesh held by the support. In the advance of the strip of plates, at each step, one plate is brought into alignment with the die members. In the period of rest between the steps, the plate which is in alignment with the dies, is struck by the dies. As the strip is advanced, the cam 89 holds the hammer away from the die against the action of the spring 83, and the coil spring 76 retracts the die 73 to allow the strip to move between the dies. During the period of rest of the strip, the cam 78 allows the spring 83 to force the hammer downwardly to cause the dies to strike the plate which is in alignment therewith. The cam then moves the rod and the hammer away from the dies and holds them in this position until the strip has again moved to bring another plate into alignment with the dies.

The dies are removable from their sockets so that they may be interchanged with dies of different designs thus permitting changes in the appearance of the finished mesh. One form of the dies is shown in Fig. 6. These dies execute the design shown in Figs. 2 and 5 which consists of a relatively large raised surface, positioned centrally of the body of each plate surrounded by a number of smaller raised surfaces. Other designs may be formed by dies of appropriate shape.

I claim:

1. A machine for making link-mesh consisting of interlocked rings and cruciform plates, comprising the combination of a support for a piece of mesh, mesh forming mechanism positioned adjacent the support, feeders for feeding the rings and the plates to the mesh forming mechanism, and a device operable to alter the surface of each plate as it is advanced to the mesh forming mechanism.

2. A machine for making link-mesh consisting of interlocked rings and cruciform plates, comprising the combination of a support for a piece of mesh, mesh forming mechanism positioned adjacent the support, a feeder for feeding the rings to the mesh forming mechanism, a feeder for feeding the plates in the form of a continuous strip to the mesh forming mechanism and a device operable to alter the surface of each plate in the strip as the latter is being fed to the mesh forming mechanism.

3. A machine for making link-mesh consisting of interlocked rings and cruciform plates, comprising the combination of a support for a piece of mesh, mesh forming mechanism positioned adjacent the support, a feeder for feeding the rings to the mesh forming mechanism, a feeder for feeding the plates in the form of a continuous strip to the mesh forming mechanism and a device for altering the surface of each plate, this device including a pair of members disposed on opposite sides of the strip and operable to treat each plate in the strip.

4. A machine for making link-mesh consisting of interlocked rings and cruciform plates, comprising the combination of a support for a piece of mesh, mesh forming mechanism positioned adjacent the support, a feeder for feeding the rings to the mesh forming mechanism, a feeder for feeding the plates in the form of a continuous strip to the mesh forming mechanism with a step by step movement, and a device for altering the surface of each plate, this device including a pair of members disposed on opposite sides of the strip and operable in timed relation to the step by step movement of the strip to act upon each plate in the strip when it is at rest.

5. A machine for making link-mesh fabric consisting of interlocked rings and cruciform plates, which comprises the combination of a support for a piece of mesh, mesh forming mechanism disposed adjacent the support, feeding mechanism for feeding plates in the form of a continuous strip to the mesh forming mechanism, feeding mechanism for supplying rings to the mesh forming mechanism, a device operable on the plates in the strip successively to alter their appearance, and power driven devices for moving the support and operating the feeding mechanisms with a step by step movement, and for operating the mesh forming mechanism and the plate altering device in the periods of rest of such movement.

6. A machine for making link-mesh fabric consisting of interlocked rings and cruciform plates, which comprises the combination of a support for a piece of mesh, mesh forming mechanism disposed adjacent the support, feeding mechanism for feeding plates in the form of a continuous strip to

- the mesh forming mechanism, mechanism for severing the plates from the strip, feeding mechanism for supplying rings to the mesh forming mechanism, a device operable 5 on the plates in the strip successively to alter their appearance, and power driven devices for moving the support and operating the feeding mechanisms with a step by step movement, and for operating the plate severing mechanism, the mesh forming mechanism and the plate altering device in the periods of rest of such movement.
7. A machine for making link-mesh consisting of interlocked rings and cruciform plates, comprising the combination of a support for a piece of mesh, mesh forming mechanism positioned adjacent the support, a feeder for feeding the rings to the mesh forming mechanism, a feeder for feeding 10 the plates in the form of a continuous strip to the mesh forming mechanism in step by step movement, a guide for supporting the strip through which the strip is fed, a device for altering the appearance of the plates 15 consisting of a pair of co-acting members disposed on opposite sides of the guide in a position such that a plate is brought into alignment with the members at each feeding movement of the strip, one of these members 20 being held stationary relative to the guide and the other being movable toward and away from the stationary member, this movable member being held normally away from the stationary member to permit the feeding 25 of the strip between the members, and mechanism operable to move the movable member toward the stationary member whereby each plate in the strip which is 30 brought into alignment with the members is 35 acted upon by the members.
8. A machine for making link-mesh consisting of interlocked rings and cruciform plates, comprising the combination of a support for a piece of mesh, mesh forming mechanism positioned adjacent the support, a feeder for feeding the rings to the mesh forming mechanism, a feeder for feeding 40 the plates in the form of a continuous strip to the mesh forming mechanism in step by step movement, a guide for supporting the strip through which the strip is fed, a device 45 for altering the appearance of the plates consisting of a pair of co-acting members disposed on opposite sides of the guide in a position such that a plate is brought into alignment with the members at each feeding 50 movement of the strip, one of these members 55 being held stationary relative to the guide, means for adjusting the position of this stationary member, the other member being movable toward and away from the stationary member, this movable member being held normally away from the stationary member to permit the feeding of the strip between the members, a hammer held normally away from the movable member, mechanism operable upon the hammer to cause the hammer to strike the movable member to move that member toward the stationary member whereby the plate which is then in alignment with the members is acted upon by the members, this mechanism being adjustable to determine the force with which the hammer strikes the movable member, and adjustable means for limiting the stroke 100 of the hammer in its movement toward the movable member of the treating device.

In testimony whereof I affix my signature.
RICHARD HATLEY BERKLEY.
